UNITED STATES PATENT OFFICE.

WILLIAM H. J. DOWNEY, OF WILMINGTON, DELAWARE.

PUT-BALL GAME APPARATUS.

1,262,314.

Specification of Letters Patent. Patented Apr. 9, 1918.

Application filed July 26, 1917. Serial No. 182,943.

To all whom it may concern:

Be it known that WILLIAM H. J. DOWNEY, a citizen of the United States, residing at Wilmington, in the county of New Castle 5 and State of Delaware, has invented certain new and useful Improvements in Put-Ball Game Apparatus; and he does hereby declare the following to be a full, clear, and exact description of the invention, such as 10 will enable others skilled in the art to which it appertains to make and use the same, reference being had to the accompanying drawings, and to the letters and figures of reference marked thereon, which form a part of 15 this specification.

This invention relates to new and useful improvements in a ball game apparatus and consists of a simple and efficient device of this nature, and is so constructed that when 20 not in use, it may be folded into a compact form.

The invention comprises various details of construction, combinations and arrangements of parts which will be hereinafter 25 fully described, shown in the accompanying drawings and specifically defined in the appended claims.

The invention is illustrated in the accompanying drawings which, with the letters 30 of reference marked thereon, form a part of the specification, and in which:

Figure 1 is a front view of the apparatus.
Fig. 2 is a central sectional view.

Fig. 3 is a view showing the apparatus 35 folded.

Fig. 4 is a perspective detail of a slight modification.

Reference now being had to the details of the drawings:

40 A designates a tray having a flange A' about the marginal edge, and feet C underneath one end and adapted to give the tray an inclination.

A platform D is provided with a flange D' 45 mounted upon the pivoted pins E and the swinging end of the said platform is without flanges and inclined and slightly curved, for the purpose of deflecting the marbles upward, as they are driven forward by the 50 hand of the operator.

A swinging frame, designated by letter F, has arms F' at its lower end, which are pivotally connected to the flanges of the tray, and said frame is provided with a series of 55 openings, designated by letter H, and are of any suitable size preferably slightly larger

than the diameter of the marble which is adapted to pass through the openings. The openings are arranged in different positions, one above another and each has a numeral 60 identifying the same, representing the count in a game, in the event of a marble passing through the opening.

A skeleton frame, designated by the letter K of bale shape, has its ends pivotally connected to the flange of the tray and its swinging end is forwardly bent, while a cloth S is fastened to the frame and serves as a means for catching the marbles. The portion of the cloth which is fastened to the 65 forwardly projecting part of the frame, is adapted to guide the marbles downwardly and when they strike the bottom of the tray will roll forward to the opening R, where they will collect and be ready for use. 70

If preferred, closures, designated by letter J, may be hinged adjacent to each opening and which, under the impact of a marble, when it comes in contact with same, will cause the door to spring down and permit 75 the marble to pass through the opening. The upper end of the swinging frame, which has the opening therein, is shouldered, as at I, shoulders adapted to engage the opposite sides of the swinging bale shaped frame and 80 serve to steady the same.

When the apparatus is not in use it may be folded down to the position shown in the drawings.

In operation, the marbles are placed upon 85 the upper surface of the platform in one of the indentures D² therein and snapped by the finger of the operator, causing the marble to be driven forward and as it comes in contact with the upwardly inclined and 90 curved portion of the platform, the marble will be directed toward the inclined frame with openings therein, and in the event of the marble passing through one or another of the openings, which are designated by 95 different numerals, the score is made. The count, in the event of the marble passing through the lower openings, and which is more easily accomplished, has the lowest 100 count, while in the event of the marble passing through the higher openings, the count is greater.

What I claim to be new is:

1. A put ball game apparatus comprising 110 an inclined tray, an apertured board hinged thereto, a protecting frame hinged to the tray and adapted to support the apertured

plate in an inclined position, and a platform over the tray and having an upwardly curved and inclined portion adapted to direct a marble toward the apertured plate, as set forth.

2. A put ball game apparatus comprising an inclined tray, a hinged apertured plate mounted on the tray, a swinging frame mounted upon the tray and having a cloth 10 covering and designed to support the said plate, and a swinging platform mounted upon the tray having an upwardly inclined end, as set forth.

3. A put ball game apparatus comprising 15 a flanged tray disposed at an inclination, a platform hinged to the flanges of the tray and having its free end upwardly inclined, a plate having openings therein provided with arms which are hinged to the tray, a 20 bale shaped frame hinged to the tray and its upper portion forwardly curved and a cloth fastened to the flanges of the tray and to said bale shaped frame and adapted to

direct the marble fired at the plate and direct the same into the tray.

4. A put ball game apparatus comprising a flanged tray disposed at an inclination, a platform hinged to the flanges of the tray and having its free end upwardly inclined, a plate having openings therein provided with 30 arms which are hinged to the tray, a bale shaped frame hinged to the tray and its upper portion forwardly curved and a cloth fastened to the flanges of the tray and to said bale shaped frame and adapted to direct 35 the marble fired at the plate and direct the same into the tray, the free swinging end of the plate being shouldered and adapted to engage the bale shaped frame to support the plate, as set forth.

In testimony whereof I hereunto affix my signature in presence of two witnesses.

WILLIAM H. J. DOWNEY.
